(57) **CLAIM**

The ornamental design for display screen or portion thereof with graphical user interface, as shown and described.

DESCRIPTION

The single FIGURE is a front view of a display screen or portion thereof with graphical user interface.

The broken lines in an equal length dash pattern illustrate an electronic device, the broken lines in a long-long-short dash pattern illustrate a boundary and portion of the display screen, and the remaining broken lines illustrate portions of the graphical user interface. None of the broken lines form part of the claimed design.
